BARBECUE UNIT

Karl M. Roth, Modesto, Calif.

Application August 14, 1951, Serial No. 16,266

Term of patent 7 years

(Cl. D81—10)

To all whom it may concern:

Be it known that I, Karl M. Roth, a citizen of the United States, residing at Modesto, in the county of Stanislaus, and State of California, have invented a new, original, and ornamental Design for Barbecue Unit of which the following is a specification, reference being had to the accompanying drawing, forming a part thereof.

Fig. 1 is a perspective view, looking at one side and one end, of a barbecue unit, showing my new design.

Fig. 2 is a similar view, but looking at the opposite side and the other end of the barbecue unit.

Fig. 3 is a perspective view of the barbecue unit, looking in the same direction as Fig. 1, but with the hood removed.

I claim:

The ornamental design for a barbecue unit, as shown.

KARL M. ROTH.
